UNITED STATES PATENT OFFICE.

EDWIN G. COX, OF OAKLAND, CALIFORNIA.

TOY VEHICLE.

1,381,403.

Specification of Letters Patent. Patented June 14, 1921.

Application filed August 20, 1919. Serial No. 318,725.

To all whom it may concern:

Be it known that I, EDWIN G. COX, a citizen of the United States, and a resident of the city of Oakland, county of Alameda, State of California, have made a new and useful invention, to wit, Improvement in Toy Vehicles; and I do hereby declare the following to be a full, clear, concise, and exact description of the same.

10 The present invention is an improved toy vehicle. The primary object of the invention is to provide a vehicle which a child rider can propel by his own effort and one which will be at the same time an amusement device and an exerciser.

Another object of the invention is to provide a vehicle on which a child may ride in an approved posture with legs and arms straight and the propulsion accomplished 20 by an anatomically correct distribution of physical effort.

Another object is to provide a manually operated toy vehicle in which the division 25 of physical labor between the arms and legs is nearly equal and in which the weight of the rider is a contributing factor in propulsion. In the vehicle hereinafter described the component mechanical parts are constructed in accordance with accepted 30 scientific principles calculated to give the maximum propulsion with the least possible physical effort. The invention resides particularly in the ingeniously fulcrumed relation of the frame to the pitman rod which 35 imparts an undulating movement of the saddle which is pleasing to a child rider.

In this specification and the annexed drawings, the invention is illustrated in the form considered to be the best, but it is to 40 be understood that the invention is not limited to such form, because it may be embodied in other forms, and it is also to be understood that in and by the claims following the description, it is desired to cover 45 the invention in whatsoever form it may be embodied.

In the accompanying two sheets of drawings,

50 Figure 1 is a side elevation of my improved toy vehicle.

Fig. 2 is a top plan view of Fig. 1.

Fig. 3 is a side elevation of my toy vehicle as it normally appears when not carrying a rider.

55 Fig. 4 is a bottom plan view showing a

gearing arrangement to accomplish the same result.

The structure herein shown comprises a three wheeled vehicle having a forward wheel 1 and rear wheels 2 and 3. The front 60 wheel 1 is pivoted on a bolt 4 extending through the bifurcated end of a steering post 6, the opposite ends of which are provided with handle bars 7-8. The rear 65 wheels 2 and 3 are journaled on the end of a crank shaft 9. The supporting frame of the vehicle consists of two side members 11 and 12, the rear downward ends of which are provided with an end mortise as shown at 13 to form bearing for the crank shaft 9 70 which is held in said mortises by bolt 14. The side members 11-12 converge toward the steering post 6 and are pivotally connected by means of the bolt 16 to a link 17 which is hingedly connected to the steering 75 post 6 by means of strap hinges 18, 19, 21 and 22 which may be of leather, rubber or any suitable flexible material and each secured at one end to the said link 17 and at the opposite end to steering post 6 in a 80 well-known manner. The side members 11 and 12 are connected intermediate their length by a cross brace 23 which also acts as a support for a reach pole 24 to which is bolted as shown at 26-27 a saddle 28 85 mounted on bolsters 29 and 31 resting on the said reach 24.

The propulsion of the vehicle is accomplished by means of the pitman 32 one end of which is journaled in the crank member 90 of the shaft 9, being rotatably secured therein by a plate 33 secured by screws 34 to the end of the pitman 32. The pitman rod 32 is bifurcated as shown in Fig. 4 and sprung apart slightly to engage the link 17, the 95 sprung ends of said pitman 32 being pivotally secured to the link 17 by a bolt 36. The bifurcated members of the pitman rod 32 are mortised as shown at 37 in Figs. 1 and 3, the purpose of the said mortises being 100 to receive and engage a foot-rest 38.

In order to overcome a dead center in the pitman rod movement, I have interposed a coil spring 39 between the fixed frame members and the pitman rod 32. In the structure here shown, I have employed one spring, the ends of which are secured in hooks 41 aligned in transverse relation to the vehicle on the foot-rest 38. The spring 39 passes through two holes in the cross brace 23 as 110

indicated in dotted lines in Figs. 2 and 3 and the spring so arranged tends to hold the structure in the position shown in Fig. 3.

The operation is as follows: A rider sitting in the saddle 28 reciprocates the handle bars 7-8 with the hands, at the same time applying forward pressure to the foot-rest 38. This applies pressure in opposite directions to the steering post 6 and link 17 which is pivoted in relation to the frame on the bolt 16 causing the vehicle to assume the position shown in Fig. 1. At this point a forward pressure is applied to the handle bars 7 and 8 which returns the mechanism to the position shown in Fig. 3. It will be seen that this movement propels the vehicle through the medium of the pitman rod 32 and at the same time produces an undulating movement on the saddle 28.

20 The expanded position of the spring 39 shown in Fig. 1 materially assists in the return of the vehicle to the position shown in Fig. 3.

In Fig. 4, I have shown a gearing arrangement wherein the usual crank shaft 9 is provided with a gear 46 which meshes with the gear 47 pinned to an axle 48. This axle carries wheels 49 and 50, also pinned or otherwise attached to the axle 48. This axle 48 is journaled in the frame members 11 and 12, as is also the crank 9 as before described.

By this arrangement, I produce a gearing for the use of grown-ups such as cripples.

Having thus described my invention, what I claim as new and desire to secure by Letters Patent of the United States is:—

1. In a device of the character described, the combination of a frame, a seat mounted thereon, a link pivoted thereto, a steering post flexibly connected to said link, a wheel carried by said steering post, a handle carried at the upper end of said steering post, a crank carried by the rear of said frame, and a pitman pivoted to said crank and pivotally connected to the lower end of said link.

2. In a device of the character described, the combination of a frame, a seat mounted thereon, a link pivoted thereto, a steering post flexibly connected to said link, a wheel carried by said steering post, a handle carried at the upper end of said steering post, a crank carried by the rear of said frame, a pitman pivoted to said crank and pivotally

connected to the lower end of said link, a 55 foot-rest carried by the forward end of said pitman, hooks carried by said foot-rest, a spring attached to one of said hooks passing through a part of said frame and having its opposite end attached to the other of said 60 hooks.

3. In a child's vehicle, the combination of a frame; a crank shaft carried at one end of said frame; traction wheels mounted on the ends of said shaft; a steering post 65 mounted at the opposite end of said frame; a connector member flexibly joined to said steering post and having said frame pivotally mounted thereon; and a connecting rod attached to said crank and pivotally secured 70 to said connector member.

4. In a child's vehicle, the combination of a frame; a seat mounted on said frame; a crank shaft carried at one end of said frame; traction wheels mounted on the ends of said shaft; a steering post mounted at the opposite end of said frame; handles carried by 75 said steering post; a connector member flexibly joined to said steering post and having said frame pivotally mounted thereon; and 80 a connecting rod attached to said crank shaft and pivotally connected to the forward end of the frame and having foot rests thereon.

5. In a child's vehicle, the combination of a frame; a seat mounted on said frame; a crank shaft carried at one end of said frame; traction wheels mounted on the ends of said shaft; a steering post mounted at the opposite end of said frame; handles carried by 85 said steering post; a connector member flexibly joined to said steering post and having said frame pivotally mounted thereon; a connecting rod attached to said crank shaft and pivotally connected to the forward end 90 of the frame and having foot rests thereon; means for rotating the crank shaft by movement of the steering post and spring means interposed between said frame and connecting rod for returning said steering post to 95 100 normal position.

In testimony whereof, I have hereunto set my hand at San Francisco, California, this 8th day of August, 1919.

EDWIN G. COX.

In presence of—

A. J. HENRY,
LINCOLN V. JOHNSON.
